(57) **CLAIM**

The ornamental design for a portable medical monitor, as shown and described.

DESCRIPTION

FIG. 1 is a front perspective view of a portable medical monitor showing our new design, and a handle of the portable medical monitor is shown in a first configuration; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a rear perspective view thereof; FIG. 9 is another rear view of the portable medical monitor, and the handle is shown in a second configuration; FIG. 10 is another left side view of the portable medical monitor, and the handle is shown in the second configuration; FIG. 11 is another rear view of the portable medical monitor, and the handle is shown in a third configuration; and, FIG. 12 is another left side view of the portable medical monitor, and the handle is shown in the third configuration. Broken lines illustrate features of the portable medical monitor that form no part of the claimed design.
